JACK

Arthur Dickerson, Salt Lake City, Utah

Application May 19, 1936, Serial No. 80,483

5 Claims. (Cl. 254—126)

My invention relates to jacks and has for its object to provide a new and efficient jack for lifting the newer types of automobiles which have so much fender extending at the rear end that it is impossible to get the ordinary jack under the axle for raising the wheel when it is desired to change a tire.

A further object is to provide a jack which will be strong and sturdy and one which will be made 10 to meet all requirements for short or great lifts.

A still further object is to provide a jack which will be compact in construction and which will be of the screw type having double reverse threaded spindle with a central support raising 15 with the screw and which jack will lift from about four and one half inches to about eighteen inches in height.

A still further object is to provide a jack which will be made of a small enough screw to have 20 sufficient strength to raise all passenger automobiles but which will also have sufficient purchase to allow it to run freely thus, providing a jack which will be easily operated and which will raise a car quickly to any desired height at the 25 same time eliminating the unnecessary raising of the entire body as is now done with bumper jacks as this jack may be slid in under the car without any trouble and is adaptable to be used directly on the axle of the car.

These objects I accomplish with the device illustrated in the accompanying drawing in which similar numerals and letters of reference indicate like parts throughout the several views and as described in the specification forming a part 35 of this application and pointed out in the appended claims.

In the drawing in which I have shown my device,

Figure 1 is a side elevation of the jack in its 40 lowered position.

Figure 2 is an end view of Figure 1.

Figure 3 is a vertical section of the jack taken at one side of the center line sectioning only the holding rivets or bolts and showing the inside of 45 the one side plate and the screw and coacting levers and foot in elevation.

Figure 4 is a side elevation of the screw spindle and operating nuts.

Figure 5 is a plan view of Figure 4.

Figure 6 is an enlarged view of the lifting foot and the top of the coacting levers.

In the drawing I have shown my jack as A, made of two opposed like sides 1 and 2, each having identical feet 3 on one end and feet 4 on the 55 other end and each being formed to fit together

to make the two sides of the jack. Medially of the two sides 1 and 2 which have the portion between the two feet 3 and 4 formed into two opposed arcs joined together at the middle, I provide a depending guide 5. This guide 5 on each side is provided with an inwardly extended guide rib 6. These two spaced apart guide ribs 6 aid in holding the jack screw C in its proper position and at the same time hold the central guide portion of the screw in proper position and the screw 10 in alignment and providing a vertical track in which this guide rides. The guide will be described later in this specification.

Extending upwardly and inwardly, continually raising as they near the center of the jack I provide two spaced apart arc shaped races 7 and 8, each side being identical in curve and form. These two arcs provide part of the raising device essential to the complete and satisfactory operation of this jack. The ends of the two arc-shaped races 7 and 8 are turned up or curved slightly upward at their lower ends to permit the lifting platform to be lowered to a greater degree than would be possible were this not so.

The two sides 1 and 2 are held together by three rivets or holding bolts 10 and 11, which extend through each side near the feet 3 and 4 and a single bolt or rivet 12 which holds the two tops of the sides 1 and 2 in firm fixed relation to each other. The screw C is made with a head B of larger diameter to which any suitable handle may be attached for rotating the screw. This screw C is made with two thread sections C1 and C2 with the section C1 to fit into the internally threaded nut 18 and the section C2 to fit into 35 the threaded nut 19 and the two threads reversed to each other, one being a right hand thread and the other being a left hand thread.

The nuts 18 and 19 are identical in form with the exception that one is threaded internally opposite to the other and each nut is provided with a stub shaft 20 extending a short distance on one side and a like stub shaft 21 extending from the opposite side thus, providing opposed stub shafts on each nut and these stub shafts carry 45 rollers 22, said rollers to operate in the two arcs 7 and 8 to aid in raising the jack platform D.

The jack platform D is curved slightly on the top side to fit it to the axle of the automobile. This platform D is made with a depending central boss in which there is a transverse slot 31 and in which slot the sliding rivet 30 is operated. The other end of this boss has a rivet 29 there-through and on these two rivets the coacting arms 23 and 24 operate and are pivoted. These 55

four arms 23 on one side and 24 on the opposite side are carried on the shafts 21 and 20 of the nuts 18 and 19 and the arms acting in pairs are crossed over and the arms or levers 23 fit onto the rivets 30 and the arms or levers 24 fit onto the rivet 29 and these four arms are each pivoted together into separate pairs one pair on each side of the screw and one pair is secured pivotally together by the rivet 27 and the other pair is secured together by the rivet 28, thus providing co-acting equal action pairs of arms or levers acting from each side of the nuts 18 and 19 to raise and lower the foot or platform D.

Medially on the screw S there is a guide member of larger diameter than the rest of the screw with the two ends 15 and 16 equal and with a central groove 17 therein, this groove operating on the spaced apart guide ribs 6.

Having thus described my invention, I desire 20 to secure by Letters Patent and claim:

1. In a jack, the combination of opposed identical sides carrying ascending arc shaped races on the inner faces, said races ascending toward the center; a depending guide rib on each side 25 medially of said races; rollers carried in said races; internally threaded nuts having extended stub shafts on each side thereof on which said rollers operate; a double screw formed with each end threaded, one with right hand threads, and 30 the other with left hand threads, said screw operating said threaded nuts; a guide medially on said screw carrying a central groove operating on said guide ribs; means to rotate said screw from one end thereof; coacting levers mounted with 35 their lower ends on the stub shafts of said nuts and made in pairs with each pair on a side riveted pivotally together near the top ends thereof; and a lifting platform mounted pivotally to like levers of the pairs of levers, with the other like 40 levers slidably mounted in a slot in said platform, said platform to be raised or lowered by the rotation of said screw.

2. In a jack, the combination of a platform on which the load is carried; two pairs of coacting 45 pivoted levers mounted to said platform; a reversely threaded screw, opposed threaded screw nuts in which said screw is operated with the lower ends of said levers connected pivotally to said nuts; and a base for said jack made of opposed identical sides having races on the inner 50 sides thereof ascending toward the middle of said base to raise and lower said nuts and levers when the screw is rotated.

3. In a lifting jack, the combination of a lifting platform having a slot longitudinally and transversely along the bottom side thereof; two pairs of coacting levers one lever of each pair pivoted to the lower side of said platform and the

other pair pivoted to a pivot pin carried in said slot; a base for said jack having arc shaped races formed therein, ascending toward the medial portion thereof; rollers carried in said races; internally threaded nuts carrying stub shafts on each side thereof on which shafts the lower ends of said pairs of levers are pivoted and on which said rollers are mounted; and a double oppositely threaded screw carried in said nuts to be manually rotated to actuate said rollers in said 10 races drawing the levers toward each other to raise the lifting platform.

4. In a lifting jack, the combination of a base formed of two like formed castings secured together having each end formed into outwardly extended feet on which the jack rests; races formed on the inner sides of each casting said races being arc shaped and ascending toward the middle of the jack with each outer end curved up slightly to allow the lifting platform to be lowered a greater degree; a central guide rib formed on each casting extending inwardly toward each other; a double oppositely threaded jack screw having a central portion with a groove therein to ride on said central guide ribs; oppositely threaded nuts carried on said screw each nut having stub shafts extended from two sides thereof; rollers mounted on the ends of said shafts and operating in said races to roll up or down said races as the screw is rotated and the nuts 30 moved in or out thereon; two sets of coacting levers mounted with their lower ends carried on said stub shafts and with their upper ends pivoted together near the top end thereof; and a lifting platform mounted at the top of said levers 35 with the pivot pin of one set of levers operating in a slot thereunder to allow for raising said platform or lowering the same.

5. In a jack, the combination of a lifting platform; two spaced apart pairs of coacting pivoted levers mounted with one pair pivoted under said platform and the other pair having a sliding mounting under said platform; a reversely threaded screw having a medial portion provided with an annular recess; opposed threaded nuts in which said screw is operated with the lower ends of said levers connected pivotally to said nuts; a base for said jack made of opposed identical sides each side having a vertical guide rib extending inwardly therein on which ribs the annular recess of the screw is operated to hold the screw in position; pairs of identical arc-shaped ascending races formed in each side of said base with the lower ends thereof curved upwardly to permit greater lowering of the lifting platform; and means to rotate said screw.

ARTHUR DICKERSON.
